UNITED STATES PATENT OFFICE.

WILLIAM FREDERICK GERHARDT AND ISAAC MACKLIN LADDON, OF DAYTON, OHIO.

MULTIPLANE.

Application filed May 29, 1923. Serial No. 642,213.

To all whom it may concern:

Be it known that we, WILLIAM FREDERICK GERHARDT and ISAAC M. LADDON, citizens of the United States, residing at Dayton, in the county of Montgomery and State of Ohio, have invented certain new and useful Improvements in Multiplanes, of which the following is a specification.

This invention relates to airplanes and particularly to airplanes of the multiplane type.

The object of the invention is to produce a multiplane which practically solves the problems of vision, performance, stability and controllability. The arrangement is such that the pilot is seated with his eyes slightly forward of the trailing edge of the aerofoil or wing surface nearest to him, enabling him to have a perfect vision either in a forward or rearward direction and thereby eliminating the blind angle formed by the aerofoil surfaces simply by leaning forward about ten inches. Furthermore, by reason of the construction herein shown and described, the machine has a minimum span and the induced drag is quite small as well as the lateral movement of inertia and dampening so that the maneuverability and controllability are unusually high. Furthermore, by reason of the extremely small chord of the aerofoil surfaces, the stability can be regulated very exactly by preliminary calculation.

With the above and other objects in view, the invention consists of the novel construction, combination and arrangement herein fully described, shown and claimed.

In the accompanying drawings:

Figure 1 is a front elevation of the improved multiplane.

Figure 2 is a side elevation of the same.

Figure 3 is a plan view thereof.

Figure 4 is an enlarged vertical transverse section through one of the aerofoils.

The airplane comprises essentially a fuselage 5 of streamline formation and of suitable length to give the requisite fore and aft stability to the machine, the fuselage having the usual vertical rudder 6 and elevator 7 and other fixed stabilizing surfaces.

The engine 8 is mounted in the nose portion of the fuselage and drives a tractor air screw 9. The pilot's cockpit 10 is arranged in rear of the engine compartment as shown in Figure 2.

The landing gear or undercarriage comprises an axle 11 and wheels 12, each of which contains a shock absorbing unit enabling the wheels to have a freedom of movement relatively to the axle to absorb all landing shocks.

13 designates a series of superimposed aerofoils of high aspect ratio. The aerofoils 13 as just shown in Figure 2 have a negative stagger formation and all of the aerofoils are connected in rigid relation to each other by means of inner struts 14 and outer struts 15. The struts 14 are fastened securely at their lower extremities to the fuselage 5 and extend upwardly through the overlying aerofoils 13. The outer struts 15 also extend through and are rigidly fastened to the aerofoils and below the level of the fuselage, the interplane struts 15 extend inwardly and form bracing members 16 which are fastened to the ends of the axle 11. Forwardly inclined braces 17 and rearwardly inclined braces 18 also connect the axle 11 to the fuselage 5.

Each of the aerofoils 13 comprises leading and trailing tubular members or spars 19 and 20, said spars conforming to the shapes of the leading and trailing edges of the aerofoil. A sheathing or cover 21 of sheet material such as metal, preferably duralumin or veneer incloses the tubular spars 19 and 20 as shown in Figure 4. The covering or sheathing 21 is preferably made of tubing which is shaped in any suitable manner to the form shown.

We claim:

In an aircraft, a plurality of superimposed aerofoils of equal dimensions, an undercarriage embodying an axle and wheels, an auxiliary aerofoil of lesser dimensions interposed between said plurality of equally sized aerofoils and the axle, a supporting strut connected to each end of said axle extending angularly outward through said auxiliary aerofoil and thence vertically through said plurality of aerofoils, said struts passing through all of said aerofoils midway between the leading and trailing edges thereof.

In testimony whereof we affix our signatures.

WILLIAM FREDERICK GERHARDT.
ISAAC MACKLIN LADDON.
